COUCH BED

Edgar O. Bartolucci, Cliffside Park, N. J.

Application November 6, 1953, Serial No. 27,458

Term of patent 14 years

(Cl. D5—4)

FIG. 1.

FIG. 2.

Figure 1 is a perspective view of a couch bed embodying my new design, the view showing the couch bed in its position of use as a couch; and

Figure 2 is a perspective view of the couch bed, the view showing the couch bed in its extended position of use as a double bed.

I claim:

The ornamental design for a couch bed, as shown.
